(57) **CLAIM**

The ornamental design for a digital readout device, as shown and described.

DESCRIPTION

FIG. 1 is a front perspective view of an embodiment of a digital readout device showing my new design;

FIG. 2 is a front view thereof;

FIG. 3 is a top view thereof;

FIG. 4 is a bottom view thereof;

FIG. 5 is a rear view thereof;

FIG. 6 is a right side view thereof;

FIG. 7 is a left side view thereof;

FIG. 8 is a front perspective view of an embodiment of a digital readout device showing my new design;

FIG. 9 is a front view thereof;

FIG. 10 is a top view thereof;

FIG. 11 is a bottom view thereof;

FIG. 12 is a rear view thereof;

FIG. 13 is a right side view thereof;

FIG. 14 is a left side view thereof;

FIG. 15 is a front perspective view of an embodiment of a digital readout device showing my new design;

FIG. 16 is a front view thereof;

FIG. 17 is a top view thereof;

FIG. 18 is a bottom view thereof;

FIG. 19 is a rear view thereof;

FIG. 20 is a right side view thereof; and,

FIG. 21 is a left side view thereof.

The broken line portions are for illustrative purposes only and form no part of the claimed design. The Figures include an illustration of the logo/written matter, "HEIDENHAIN," which is shown for illustrative purposes and forms no part of the claimed design.
